UNITED STATES PATENT OFFICE.

CARL O. WALLISER, OF CHICAGO, ILLINOIS, ASSIGNOR TO H. F. WALLISER COMPANY, OF CHICAGO, ILLINOIS, A CORPORATION OF ILLINOIS.

DESIGN FOR EDGING.

Application filed May 10, 1923. Serial No. 6,127. Term of patent 14 years.

To all whom it may concern:

Be it known that I, CARL O. WALLISER, a citizen of the United States, residing at Chicago, in the county of Cook and State of Illinois, have invented a new, original, and ornamental Design for Edging, of which the following is a specification, reference being had to the accompanying drawing forming a part thereof, in which the figure of drawing is a face view of a portion of said edging showing my new design.

I claim:

The ornamental design for edging as shown.

CARL O. WALLISER.
